UNITED STATES PATENT OFFICE.

ALBION A. VANDERPOOL, OF NEWARK, NEW JERSEY.

GUIDE FOR T SQUARES.

Application filed August 12, 1922. Serial No. 581,293.

To all whom it may concern:

Be it known that I, ALBION A. VANDERPOOL, a citizen of the United States, and a resident of Newark, county of Essex, and 5 State of New Jersey, have invented certain new and useful Improvements in Guides for T Squares, of which the following is a specification.

This invention relates to an improved 10 guide for insuring the smooth and firm contact of the head of a T-square against the edge of a drawing board so that the draftsman is relieved of the necessity of observing whether the head of the square is against 15 the board or not.

The invention has for its object to provide such a guide in which the placing of the T-square against the board, its manipulation and its removal are as easy as with a T- 20 square without the attachment, and further, to provide a guide having no parts in the way of the draftsman to interfere with the normal operation of the square.

The invention is illustrated in the accompanying drawing, in which Figure 1 is a perspective view of the parts constituting the invention, with the drawing board and the T-square indicated in dotted outline. Figure 2 is a section of the edge of the board 25 and part of the T-square, and with the slide and strip of the invention in position. Figure 3 is a section of the slide taken on line 3-3 in Figure 1, and Figure 4 is a perspective of an abutment used on the slide.

In the drawing the drawing board is indicated at 10 and the T-square is indicated at 11 with the usual head 12 and the blade 13. In the drawing the head of the T-square is shown as used for securing the slide 14 to 30 the square, although various places and means for attachment can be used.

In the form shown, the slide 14 is of metal and its two edges 15 and 16 are parallel, insuring the same relation of the square to the board as when it is omitted. The various sizes of T-square heads can be accommodated, since the abutment or stop 17 is adjustable and is held in place by the screw 18 45 preferably operating in a T-slot 19 in the slide 14 and having a nut 20 to bind the head of the screw in the slot. The foot 21 of the abutment or stop 17 engages one end of the head of the square, and the binding screw 22 is screwed up tight to hold the head of the 50 square in the slide. The slide moves freely along the edge of the board and is held up 55

tight against the board by suitable springs, such as the leaf springs 23 which bear against and slide freely along the flange or strip 24, usually in the form of an angle iron 60 and fastened as by the screws 25 to the bottom of the board.

The T-square can be placed against or removed from the board with no particular manipulation, because the fingers of the 65 hand holding the head of the square can press in on the springs 23 to enable the slide 14 to be slid in edgewise between the strip 24 and the end of the drawing board.

The advantage of this device is that when 70 the T-square is equipped with it the accidental shifting of the blade of the square is prevented. It often occurs that a loose square becomes slightly out of line, especially a long square, and such condition is 75 sometimes present a long time before it is detected, so that much faulty work must be erased. With this device the head of the square is positively and firmly held against the edge of the board and the square can be 80 slid up and down without necessarily taking hold of the head of the square, and can be moved, if desired, from the blade alone.

I claim:

1. A guide for T-squares comprising a 85 slide for attachment to the guiding edge of the head of the T-square, a strip adapted to be secured to a drawing board, and yielding means adapted to be interposed between the slide and the strip for holding the guide 90 against the drawing board.

2. The combination of a drawing board and a T-square, with a guiding strip secured to the board, a slide secured to the square, and spaced springs interposed between the 95 strip and the slide, said springs being disposed to normally force the guide against the board and to permit the edgewise insertion and withdrawal of the slide.

3. The combination of a drawing board 100 and a T-square, with a guiding strip secured to the board and spaced from its edge, a slide secured to the head of the square and adapted to be interposed between the said edge and the strip, and spaced springs on 105 the slide and bearing on the strip to hold the head of the square against the edge of the board.

4. A guide for T-squares comprising a flat slide having clamping means at its top edge 110 for securing it to the head of a T-square, and having springs projecting beyond its face

near the bottom, and a track for attachment to a drawing board, said track including a flange to act as an abutment for the springs.

5. A guide for T-squares comprising a flat slide having an adjusting screw on one end at the top and having an adjustable stop at the other end, whereby the slide can be secured to the head of a T-square and perpendicular to the blade, and having springs pro-

jecting beyond its face near the bottom, and a track for attachment to a drawing board, said track including a flange to act as an abutment for the springs.

In testimony that I claim the foregoing, I have hereto set my hand, this 20th day of 15 July, 1922.

ALBION A. VANDERPOOL.
